UNITED STATES PATENT OFFICE.

EDWARD HAUSER, OF NEW YORK, N. Y.

ELASTIC HOSIERY SUPPORTER.

Application filed March 6, 1922. Serial No. 541,379.

To all whom it may concern:

Be it known that I, EDWARD HAUSER, a citizen of the United States, residing at New York, in the county of New York and 5 State of New York, have invented new and useful Improvements in Elastic Hosiery Supporters, of which the following is a specification.

This invention relates to improvements in 10 hose supporters.

The primary object of this invention is the provision of a supporter so constructed as to prevent "runs" in the hose, which are so often caused by the present form of 15 garters.

Another object of the invention is the provision of a supporter consisting of a strip of elastic with means for adjusting 20 the length and a novel form of clamp secured to each end thereof. One clamp being capable of engagement with the corset, waist belt, brassière or some garment of the wearer, and the other of said clamps adapted to engage the hose at the top thereof.

25 Another object is to provide a novel form of clamp capable of securely holding the stocking in position at all times, thereby eliminating all possibility of slipping.

Another object is to provide a supporter 30 which not only involves simplicity, cheapness and durability but one which may be worn with great comfort.

With these and other objects in view 35 which will be more apparent as the nature, purpose and use of the invention is better understood from the following description and claim taken in connection with the accompanying drawings, in which:—

Figure 1, is a perspective view showing 40 my improved supporter as applied to the wearer.

Figure 2, is a front elevation thereof.

Figure 3, is an edge view partly in section.

Figure 4, is a detail view of the same.

45 Figure 5, is a front view showing a slight modification.

Figure 6, is a view showing a further modification.

50 Figure 7, is a rear view of the clamp showing a slightly modified form.

Heretofore, great difficulty has been experienced in preventing "runs" in hose, due to the tightness of the garter and the style of clamp used. This has proven to be very 55 costly and it is thought that with the form

of supporter about to be described, the above difficulties will be avoided.

Referring more particularly to the preferred form of supporter shown in Figures 1, 2, 3 and 4, the numeral 10 indicates my 60 improved supporter as a whole, which consists of a strip of elastic 11, to which is secured my novel form of clamps 12 and 13. The clamp 12 is stitched to the elastic 11, and intended for clamping engagement 65 with the corset 14 as shown, but the same may be fastened to a waist belt, brassière or some other suitable garment of the wearer. The clamp 13 is carried by a loop formed in the elastic and is capable of engagement with the top of a stocking 15. A buckle 16 may be used for adjusting the 70 length of the supporter.

For the reason that both the clamps 12 and 13 are identical in construction, it is 75 thought only necessary to describe one of them. Each clamp comprises a U-shaped body portion 17 having pivoted thereto a suitable means 18 for connection with the elastic. A strip of spring metal 19 has one 80 end secured to the U-shaped body member 17, the free end of the spring 19 having a cover of thin ribbed rubber 20. The rubber covering 20 has a plurality of projections 21 thereon. A lever 22 is pivoted at 23 to 85 the outside of the U-shaped body portion 17; the lever 22 is provided with a curved offset portion 24, for engagement with the free end of the spring 19. It will be seen 90 that by manipulation of the lever 22, a clamping action may be set up between the spring 19 and the back wall 25 of the U-shaped member 17. By providing the ribbed rubber covering over the free end of the 95 spring and forming the projections thereon, the possibility of any slipping action between the clamp and the garment is reduced to a minimum.

It will be seen that I have provided a supporter which may be detachably secured to a corset or the like, but if 100 desired this end may be permanently attached thereto by stitching the elastic to the garment thereby only using one clamp.

In Figure 5, I have shown a slightly modified form in which one clamp is used 105 for engagement with the corset and two clamps for attachment to the hose.

Figure 6, shows a further modification in which the preferred form is used, but to 110 which is attached an ordinary circular

garter 26. By this arrangement there is provided a double supporter.

If desired, a clamp 27 as shown in Figure 7, may be provided with a backing of fabric 28, thereby preventing any metal from coming in contact with the skin of the wearer.

Having described what I consider to be the best embodiment of my invention, I wish it to be understood that changes and alterations which come within the claim may be resorted to when so desired.

What is claimed as new is:—

A hose supporter clamp comprising a substantially U-shaped body portion having one

arm slotted, a strip of spring metal having one end secured to the opposite arm and being bent to position the opposite end of said strip adjacent the terminals of the body portion, a lever pivotally secured to the slotted arm, a curved off set portion formed on the lever and extending through the slot to engage the strip for the actuation thereof, and a covering provided for a portion of the strip as and for the purpose specified.

In testimony whereof I have affixed my signature.

EDWARD HAUSER.
